US00D916152S

(12) **United States Design Patent** (10) **Patent No.:** **US D916,152 S**
(45) **Date of Patent:** **** Apr. 13, 2021**

(54) **COMPRESSION LIMITER**

(71) Applicant: **APQ Development, LLC**, Jackson, MI (US)

(72) Inventors: **Lee McLain**, Jonesville, MI (US); **Justin Joughin**, Morenci, MI (US)

(73) Assignee: **APQ Development, LLC**, Jackson, MI (US)

(**) Term: **15 Years**

(21) Appl. No.: **29/747,583**

(22) Filed: **Aug. 24, 2020**

(51) LOC (13) Cl. **15-09**

(52) U.S. Cl.

USPC **D15/138; D15/150**

(58) **Field of Classification Search**

USPC 15/5, 138, 150, 151, 152; D23/262
CPC B22F 3/02; B22F 2003/031; B22F
2003/033; F16B 5/025; F16B 19/02;
F16B 41/002

See application file for complete search history.

Primary Examiner — Patricia A Palasik

(74) Attorney, Agent, or Firm — Honigman LLP; Brett A. Krueger

(57) **CLAIM**

The ornamental design for a compression limiter, as shown and described.

DESCRIPTION

FIG. 1 is top-front perspective view of a compression limiter, showing my design;
FIG. 2 is a bottom-rear perspective view thereof;
FIG. 3 is a top view thereof;
FIG. 4 is a bottom view thereof;
FIG. 5 is a front view thereof;
FIG. 6 is a rear view thereof;
FIG. 7 is a right side view thereof; and,
FIG. 8 is a left side view thereof.

1 Claim, 8 Drawing Sheets
